GAME

Theodore Gensmer, Portland, Oreg.

Application September 9, 1931, Serial No. 561,855
Renewed December 18, 1934

1 Claim. (Cl. 273—129)

This invention relates generally to devices for shooting pellets, particularly marbles, and a target and playing surface especially designed for use in conjunction therewith.

5 The main object of this invention is the construction of an exceedingly simple and efficient form of a pellet projecting apparatus, together with a unique form of target and return ball apparatus in which the pellet, after being discharged, will finally return to the player's end of the board.

The second object is the construction of a pellet projecting apparatus of the repeater type from a plain block of wood with the addition of a simple plunger and a pair of rubber bands.

15 The third object is to introduce into the game a definite amount of noise when the shot is fired and a corresponding sound when the target is struck.

20 The fourth object is to so construct the projecting apparatus that it may be manufactured at an extremely light cost by means of ordinary woodworking materials, thereby giving employment to large numbers of people and placing same within the range of people of extremely moderate means.

These, and other objects, will become more apparent from the specification following as illustrated in the accompanying drawings, in which:

30 Fig. 1 is a side elevation of the projecting apparatus with a portion cut away in section.

Fig. 2 is a front elevation of Figure 1.

Fig. 3 is a section taken along the line 3—3 in Fig. 2.

35 Fig. 4 is a vertical section taken along the line 4—4 in Fig. 3.

Fig. 5 is a section taken along the line 5—5 in Fig. 1.

Fig. 6 is a side elevation of an alternative form 40 of the device.

Fig. 7 is a front elevation of the form shown in Fig. 6.

Fig. 8 is a perspective view of the target apparatus showing the projecting device mounted 45 thereon when not in use.

Fig. 9 is a plan of the target apparatus,

Fig. 10 is a perspective view of the target itself.

Fig. 11 is a perspective view of one of the target side walls.

50 Fig. 12 is a perspective view of the rear wall of the target apparatus.

Fig. 13 is a perspective view of the projecting apparatus, the target apparatus and a return ball board upon which the game is played.

Fig. 14 is a section taken along the line 14—14 in Fig. 13.

Similar numbers of reference refer to similar parts throughout the several views.

Referring in detail to the drawings, the projecting apparatus consists of an elongated block of wood 16 having its top side 17 sloping downwardly toward the muzzle 18. Parallel with the base 19 is formed a hole 20 in which is mounted a plunger 21 having an enlarged head 22 which is normally held against the breech end 23 by a rubber band 24 disposed within a vertical slot 25 which extends into the opening 20. The rubber band 24 is fastened at the muzzle end to a transverse nail 26 and at its rearward end to the plunger 21 by means of a brad 27.

A single-shot loading hole 28 extends downwardly through the top side 17 and communicates with a substantially horizontal hole 29 equal in diameter to the hole 28. The hole 29 constitutes the bore of the apparatus.

Parallel with the top side 17 is a magazine hole 30 which extends from the breech 23 to the hole 28. In the sides 31 are formed the grooves 32 which register at the muzzle end with the slot 33. A rubber band 34 occupies the grooves 32 and the slot 33 and has a two-fold purpose. First, it offers a slight amount of resistance to the pellet 35 when in the position shown in Fig. 3, as well as providing a cushion stop for the pellets moving downwardly through the magazine hole 30. Second, the band 34 forms a closure for the breech end of the magazine hole 30 past which the pellets 35 can be easily forced when loading the magazine.

The operation of this form of the device is exceedingly simple. It is loaded by merely inserting the pellets or marbles 35 into the magazine hole 30 by way of the breech 23, or through the hole 28, which is also used for single-shot purposes and for observing whether or no a charge remains in the base.

In order to project the pellets 35 it is necessary to hold the block 16 with one hand and withdraw the head 22 with the other hand, aiming it, of course, by sighting along the sides of the block. Releasing the head 22 causes the plunger 21 to sharply strike the lowermost pellet 35 and propel it from the bore 29.

This operation may be repeated as often as there are pellets in the magazine, and in some instances it will be found desirable to form a slot 36 only or partly through the top side 17 into the opening 30.

In the form of the device shown in Figs. 6 and 7

55

there is illustrated the projecting apparatus mounted on wheels 37 in order to make same portable and more nearly resemble a field piece. The number and arrangement of such wheels 5 may of course be varied greatly without departing from the spirit of this invention.

The target of this device consists of an up-right wall 38 having the openings 39 formed in the bottom edge thereof and an intermediate opening 40 formed a slight distance from the bottom edge 41. The bottom edge 41 has also a pair of slots 42 which receive the notched portions 43 of the side walls 44 whose rearmost ends 45 are held together by a back wall 46. The notches 15 47 of the wall 46 match with the notches 48 of the side walls 44. The wall 46 supports a bell 49 which will be struck by any pellet 35 passing through the openings 39 or 40. The bell 49 is directly in line with the opening 40 and any pellet 20 35 passing through the opening 39 is deflected against the bell 49 by the side wall 44.

It is desirable to place the target and the projecting apparatus on a plane surface 50, which forms the top of a playing board which is supported by the side walls 51 between which is an inclined sub-floor 52 which slopes laterally and longitudinally, as illustrated, for the purpose of returning balls which find their way into the target enclosure to the operator. The top surface 30 50 has an opening 53 through which the pel-

lets find their way downwardly onto the floor 52. I claim:

A marble projecting apparatus comprising a longitudinal block of wood having a horizontal base and vertical sides and ends, and having its top side sloping from end to end, said block having a horizontal plunger hole formed lengthwise therethrough adjacent to said base, said plunger hole terminating in an enlarged marble projecting bore at the lower end of said block and having a longitudinal vertical slot formed through the bottom of said block communicating with said plunger hole, a plunger mounted in said plunger hole, an elastic band within said slot having one end fastened to said block and the other end to 15 said plunger, said block having a sloping magazine hole formed in the upper portion thereof and having a vertical loading hole formed in the lower end of said block extending from its top side down past said magazine hole with which it 20 communicates into said marble projecting bore, said block having lateral slots formed therein on opposite sides of said magazine hole, and a continuous rubber band occupying said lateral slots one portion of which intersects said magazine 25 hole within said loading hole and another portion of which intersects the upper end of said magazine hole.

THEODORE GENSMER.
